UNITED STATES PATENT OFFICE.

LUELLA L. GOOLD, OF ARLINGTON, MASSACHUSETTS, ASSIGNOR TO SEMI-UNIT CORPORATION, OF ARLINGTON, MASSACHUSETTS, A CORPORATION OF MASSACHUSETTS.

HYPODERMIC SYRINGE.

1,388,946.

Specification of Letters Patent. Patented Aug. 30, 1921.

Application filed May 18, 1920. Serial No. 382,445.

To all whom it may concern:

Be it known that I, LUELLA L. GOOLD, a citizen of the United States, residing at Arlington, in the county of Middlesex and 5 State of Massachusetts, have invented new and useful Improvements in Hypodermic Syringes, of which the following is a specification.

This invention relates to a hypodermic 10 syringe, comprising a collapsible container in which a charge of liquid serum, or other medicament is hermetically sealed, and a hypodermic needle having a rigid hub secured to the container, the syringe being 15 provided with a rupturable closure between the needle hub and the charge of liquid, normally preventing the passage of liquid to the needle, and with means for causing rupture of the diaphragm when pressure is 20 exerted on the container to collapse the same.

The object of the invention is to provide improved means for connecting the needle hub with the container, and for confining 25 the diaphragm in such manner as to provide a liquid-tight joint and permit the rupture of the diaphragm when pressure is exerted on the container.

The invention is embodied in the improvements which I will now proceed to describe 30 and claim.

Of the accompanying drawings forming a part of this specification,—

Figure 1 is a side elevation of a hypodermic syringe embodying the invention.

Fig. 2 is an enlarged section on line 2—2 of Fig. 1.

Fig. 3 is an enlargement of portions of Fig. 2, showing the parts separated.

Fig. 4 is a view similar to a portion of Fig. 2, showing a modification.

The same reference characters indicate the same parts in all of the figures.

In the drawings, 12 represents a collapsible tube made of any suitable ductile metal or alloy, open at one end and closed at the opposite end, the tube being preferably a cylindrical cup, the bottom of which constitutes the closed end. Surrounding the 50 open end is an annular outwardly projecting flange 13. 14 is a flexible and easily rupturable diaphragm, which is preferably a disk of tin foil, considerably thinner than

the wall and flange of the tube, and seated on the flange 13. 15 represents a rigid metal hub, to which is attached a hypodermic needle 16. The hub is provided with a rigid annular face 17, seated on the marginal portion of the diaphragm, or that portion which bears on the flange 13. The face 17 is preferably formed on a rigid annular flange 18, integral with the hub.

A coupling member is provided, having means for exerting pressure on the tube flange and on the needle hub, to clamp the marginal portion of the diaphragm between said flange and hub, and thus form a liquid-tight joint.

The said coupling member is preferably composed of an annular jaw portion 21, seated on the flange 13, and a sleeve portion 22, crimped against the marginal portion of the hub, as shown by Fig. 2, the said coupling member being made of a suitable ductile metal or alloy. In crimping the sleeve portion 22, sufficient pressure is exerted to cause the annular face 17 and jaw portion 21, to compress the portion of the diaphragm between the flange 13 and the annular face 17. Said face is preferably formed as a bead adapted to indent the diaphragm, and thus form an annular weakened line thereon, so that when collapsing pressure is exerted on the tube 12, the resulting pressure of the liquid on the diaphragm will break the latter at said weakened line, or a part thereof, and permit the liquid to pass through the diaphragm. The inner end of the hub 15 is preferably provided with a recess 24, into which a portion of the ruptured diaphragm may be forced, the receiving end of the needle 16 being spaced from the diaphragm when the latter is intact. The coupling member may be otherwise formed and applied. Fig. 4 shows a two-part coupling member, one part of which includes a jaw portion 25, and an internally threaded sleeve portion 26, the other part including an externally threaded clamping ring or jaw 27, screwed into the sleeve 26, and bearing on the marginal portion of the hub.

The needle 16 may be provided with a penetrating point 28 at its inner end, adapted to puncture the diaphragm when the latter is flexed into the recess 24. Fig. 4 shows

a flat annular clamping face 17^a, instead of the beaded face 17.

I claim:

1. A hypodermic syringe comprising a collapsible tube, open at one end and having an annular outwardly projecting flange surrounding the open end, the opposite end of the tube being hermetically closed, a flexible and easily rupturable diaphragm seated at 10 its marginal portion on said flange, and forming a closure for said open end, a rigid needle hub having an annular clamping face, seated on the marginal portion of said diaphragm, a hypodermic needle secured to said hub, and 15 a coupling member having means exerting clamping pressure on the tube flange, and on the hub, to clamp the marginal portion of the diaphragm between said flange and the annular face of the hub.
- 20 2. A hypodermic syringe substantially as specified by claim 1, the coupling member being composed of an annular jaw portion seated on the tube flange, and a sleeve portion crimped against the marginal portion of 25 the hub to clamp the marginal portion of the diaphragm between said flange and the annular face of the hub.
3. A hypodermic syringe substantially as 30 specified by claim 1, the hub being provided with a recess surrounded by said annular clamping face, to permit outward flexure of

the central portion of the diaphragm when pressure is exerted on the tube.

4. A hypodermic syringe substantially as 35 specified by claim 1, the said annular clamping face being formed to indent the marginal portion of the diaphragm, and thereby weaken said portion to facilitate rupture of the diaphragm.

5. A hypodermic syringe comprising a collapsible tube open at one end and having an annular outwardly projecting flange surrounding the open end, the opposite end of the tube being hermetically closed, a flexible and easily rupturable diaphragm seated at 45 its marginal portion on said flange, and forming a closure for said open end, a rigid needle hub, having an annular flange seated on the marginal portion of said diaphragm, one side of said flange forming an annular 50 clamping face, a hypodermic needle secured to said hub, and a malleable coupling member, including an annular flange seated on one side of the tube flange, and a sleeve integral with said flange, and crimped against 55 the outer side of the hub flange, to exert clamping pressure on the tube flange and on the hub flange.

In testimony whereof I have affixed my signature.

LUELLA L. GOOLD.
